UNITED STATES PATENT OFFICE.

DON GAULT, OF EAST LAKE, TENNESSEE, ASSIGNOR TO THE GUARDIAN SAVINGS AND TRUST COMPANY, OF CLEVELAND, OHIO, A CORPORATION OF OHIO.

BOX-FORMING MACHINE.

Application filed July 14, 1923. Serial No. 651,504.

To all whom it may concern:

Be it known that I, DON GAULT, a citizen of the United States, and resident of East Lake, in the county of Hamilton and State 5 of Tennessee, have invented certain new and useful Improvements in Box-Forming Machines, of which the following is a specification.

This invention relates in general to a box-forming machine and particularly refers to the parts of such machines for uniting the end flaps of paper box blanks after the blanks have been subjected to the gumming steps in the process of manufacturing the 15 same.

It is a usual practice for the manufacturers to cut and score the blanks, and ship them in flat condition to the user, and for the user to glue the ends or flaps. Such machines are often used where there is only a 20 limited source of power available and yet the sealing of the glued ends of the boxes requires the application thereto of relatively great pressure, and also where the operators 25 of the machine are of the unskilled type of labor, likely to damage the boxes, the machines or the blanks unless special means be provided to prevent such damage.

Accordingly, one of the primary objects 30 of the invention is to provide a pressing or clamping machine of simple and rugged construction, which may be operated in an efficient manner, and at the same time effectively prevent damage to parts or material 35 should the machine be operated unskillfully.

Another object relates to a novel combination of massive jaw elements, the movable one of which is operated through a toggle mechanism and is therefore subjected to 40 powerful leverage effects, and means to prevent the effective operating pressure of the movable jaw from exceeding a definite predetermined amount.

Another object relates to the provision of 45 means for varying the maximum amount of pressure applied by the movable jaw.

Various other objects and advantages of the invention will be in part obvious from 50 an inspection of the accompanying drawing and in part will be more fully set forth in the following particular description of one form of mechanism embodying my invention, and the invention also consists in certain new and novel features of construction

and combination of parts hereinafter set forth and claimed.

The accompanying drawing shows a side elevation with parts broken away of one embodiment of the invention.

In the following description and in the 60 claims, parts will be identified by specific names for convenience of expression but they are intended to be as generic in their application to similar parts as the art will permit.

In the drawing there is shown a heavy 65 base 10 to accommodate the actuating mechanism of the machine and to form a support therefor. The base is provided on one side with an upright pillar 11 to the front face of which is bolted a heavy casting herein-after identified as a jaw post guide 12, and which is substantially of the same height as the pillar 11.

The upper portion of the guide 12 is provided with a forwardly extending projection 75 13 in the form of a massive ledge or anvil constituting the fixed jaw of the pressing machine. The ledge 13 in the embodiment shown is separably mounted on the guide 12, and forms a die especially designed so as to 80 receive the particular form of box element which is desired to be pressed. By substituting a different form of die different types of articles may be pressed as desired.

The guide 12 is of channel shape and is 85 provided adjacent its upper end with a relatively large pin 14 extending through the guide 12. The guide 12 constitutes a relatively long, vertically disposed guide-way in which is slidably mounted a jaw post 17 90 which is shaped to fit snugly in the guide-way of the guide 12. The upper end of the post 17 is provided with a forwardly extending head 18 constituting a movable jaw of the pressing machine. The head 18 is of 95 sufficiently massive construction to resist distorting strains when in use.

For guiding the pin 14 in its vertical reciprocatory motion there are provided in the sides of the jaw post 17 vertically extending slots 21, in which the pin 14 fits snugly but without binding. The lower end of the movable jaw post 17 is provided with a forwardly extending foot 22 through which extends a shouldered nut 50 slidably 100 mounted therein and adjustably mounted upon a threaded stud 51 forming part of the toggle mechanism described hereinafter. On

- the upper face of the foot 22 and surrounding the upper end of the nut 50 is mounted a washer 52 forming the seat for a compression spring 53. An adjustable nut 54 5 mounted on the stud 23 determines the normal resiliency of the spring 53 and limits positively the relative movement of the foot 22 and the nut 50 as will be described more fully hereinafter.
- 10 For reciprocating the movable jaw post 17 in the guide-way formed by the guide 11 there is provided a toggle 25, pivotally connected at its upper end to the pin 14, and at its lower end to the stud 23 through a 15 pivotal joint 26. The toggle comprises an upper link 27 and a lower link 28, which are pivotally interconnected by a pin 29. The pin 29 is operatively connected to a horizontally disposed eccentric strap 30 20 which is actuated by an eccentric 31 loosely mounted on a constantly driven drive shaft 32 journaled in the frame of the base 10. The shaft 32 may be driven in any suitable manner as by means of a pulley and fly- 25 wheel 33 operatively connected to a source of motive power and geared through a reducing gear connection 34. The eccentric 31 is driven from the shaft 32 through a ratchet 35 fixed to the shaft and a pawl 37 pivotally 30 mounted on the enlarged portion of the eccentric 31. The pawl 37 is normally maintained in operative engagement with its ratchet 35 by means of a spring 38. A sliding bolt 39 is slidably mounted in the frame 35 of the base 10 and is normally positioned in the path of movement of the revolving pawl so as to cause the pawl to be withdrawn from the ratchet when the eccentric has completed its cycle of movement.
- 40 For controlling movement of the sliding bolt 39 there is provided a pedal 40 in convenient reach of the foot of the operator, and operatively connected with the bolt 39 by means of a system of reach-rods and bell 45 crank levers 41. The pedal 40 is held in its upper position, and the bolt 39 is held in projected position, normally, by means of a tension spring 42.
- 45 The shaft 32 may be utilized as a source 50 of power for actuating other elements of the machine, such for example, as the gluing roller (not shown), and for this purpose the shaft is provided with a driving gear 43 affixed thereto.
- 55 In operation, assuming the parts are in the position shown in Figure 1 with the flywheel 33 in active operation and flaps of the box to be glued in condition ready for the pressing operation, the flaps are inserted in position on the fixed jaw 13 and beneath the movable jaw 18. When the operator steps on the pedal 40, the bolt 39 is withdrawn from its pawl holding position. Under control of the pawl actuating spring 60 65 38 the pawl 39 is thereupon moved into engagement with the actively rotating ratchet 35. The rotating ratchet picks up the pawl and acts therethrough to rotate the eccentric 31. The strap 30 is moved thereby and reciprocates the mid-portion of the toggle 25. As the upper end of the toggle is held relative to the machine as a whole by the pin 14 on which the toggle link 27 is pivoted, the action of the toggle is first to effect a downward movement of the lower end of the toggle comprising the stud 23, and the nuts 50 and 54 mounted thereon. 70
- This movement is imparted to the foot 22 of the jaw post 17 through the heavy compression spring 53, which is preferably of such size and construction as to withstand a heavy pressure before yielding. I have found a spring yielding to about 150 pounds pressure to give good results. 80
- The action of the toggle thus effects a downward movement of the movable jaw post 17, causing the upper jaw 18 to approach the fixed lower jaw member 13. On the succeeding movement of the eccentric 31 the strap 30 is moved in the opposite direction and the movable jaw post 17 and jaw 18 retracted, to assume the initial position. This action will continue, the movable jaw reciprocating up and down in its guide-way as long as the operator holds the pedal 40 85 down and the bolt 39 in its operative position to permit the revolving pawl to clear the same. As soon as the operator releases the pedal 40 it returns to its upper position as shown under control of the spring 42 and the bolt is again positioned in the path of the pawl 32, which thereafter comes in contact with the bolt 39, is rotated on its pivoted mounting and cleared of the revolving ratchet. The machine is thus brought automatically into its initial position and is ready for the succeeding pressing operation. 105
- Should there be any foreign material inserted inadvertently between the jaws, such, for example, as a screwdriver or other tool, 110 the operation will be as follows: Assuming the parts are in position shown in Figure 1 with the flywheel 33 in active operation and with some foreign material inserted between the jaws 18 and 13 preventing them from fully closing, and assuming that the operator inadvertently steps on the pedal 40, or has stepped thereon before the insertion of the foreign material was noticed, 115 the bolt 39 is drawn from its pawl-holding position as before. The eccentric 30 is thereupon rotated and reciprocates the mid-portion of the toggle 25 to effect a downward movement of the lower end of the toggle comprising the stud 23 and the nuts 50 and 54 mounted thereon. This movement 120 is imparted to the foot 22 of the jaw post 17 through a heavy compression spring 53 and causes the upper jaw 18 to move downwardly. Upon contacting with the tool or 125 130

whatever foreign material has been inserted between the jaws, subsequent movement of the jaw 18 and movable jaw post 17 is prevented, but continued movement of the toggle 5 is taken up in the compression spring 53 and serious damage to the jaws 18 and 13 is thus prevented. Subsequent movement of the eccentric 31 releases the spring 53 and restores the jaw 18 to normal position, and it may be assumed that by this time the operator has noticed that something is wrong and releases the pedal 40. The machine is thereupon brought automatically into its initial position as has been previously described and is stopped therein by release of the pawl 39. The amount of pressure exerted by the compression spring 53 may be variably adjusted by means of the adjusting nut 54 which may be moved 20 downwardly to increase the pressure and upwardly to reduce the pressure and thus to vary the cushioning effect upon the movable jaw.

Thus it will be seen that I have provided 25 a box-forming machine of simple and rigid construction, but capable of applying great pressure to the box to be formed so as to properly seal the same; and having a positive limitation upon the pressure applied 30 in order effectively to prevent the application of excessive pressure so that damage to the machine, if tools or other foreign devices are placed in the machine while in operation, may not occur.

The machine of the present invention permits the employment of expensive dies or other forming apparatus in order to emboss the box being formed in a predetermined manner, and effectively prevents damage to 40 such expensive tools should the power be applied at a time when foreign objects are in the path of the movable jaw of the machine.

While I have shown and described and 45 have pointed out in the annexed claims certain novel features of my invention, it will be understood that various omissions, substitutions and changes in the form and details of the device illustrated and in its operation may be made by those skilled in the

art without departing from the spirit of my invention.

Having thus described my invention, I claim:

1. In a box-forming machine, the combination of a movable jaw, a toggle for reciprocating the same, driving mechanism for actuating the toggle, and resilient cushion means for cushioning the blow of the movable jaw to limit the pressure applied 55 thereby.

2. In a box-forming machine, the combination of a movable jaw, a toggle for reciprocating the same, driving mechanism for actuating the toggle, resilient cushion 65 means for cushioning the blow of the movable jaw to limit the pressure applied thereby, and means for adjusting the cushioning effect of said resilient stopping means.

3. In a box-forming machine, the combination of a stationary jaw and a movable jaw, a guidepost for supporting the stationary jaw and having aligned channels, a movable jaw post for supporting the movable jaw and movable in said channels, a 75 stud slidably mounted in said movable jaw post, a compression spring held in fixed position by said stud and means for intermittently applying the pressure through said spring to said movable jaw post for reciprocating the movable jaw.

4. In a box-forming machine, the combination of a stationary jaw, a guidepost supporting said jaw, a movable jaw and a movable jaw post slidably mounted in said 85 stationary jaw, a compression spring mounted upon said jaw post, and means operative through said spring for reciprocating the movable jaw post and movable jaw.

5. In a box-forming machine, the combination of a stationary jaw and a movable jaw, a channeled post for supporting the movable jaw, and means positioned on a portion of said movable jaw post for limiting the pressure which can be applied to 90 said jaws.

Signed at Chattanooga, in the county of Hamilton and State of Tennessee, this 10th day of July, A. D. 1923.

DON GAULT.
